UNITED STATES PATENT OFFICE.

PETER H. ALBERT, OF VULCAN, MICHIGAN.

COW-TAIL HOLDER.

1,274,356.

Specification of Letters Patent. Patented July 30, 1918.

Application filed May 2, 1918. Serial No. 232,059.

To all whom it may concern:

Be it known that I, PETER H. ALBERT, a citizen of the United States, residing at Vulcan, in the county of Dickinson and 5 State of Michigan, have invented certain new and useful Improvements in Cow-Tail Holders; and I do hereby declare the following to be a full, clear, and exact description of the invention, such as will enable 10 others skilled in the art to which it appertains to make and use the same.

This invention comprehends generally improvements in that class of inventions known as animal husbandry and more particularly relates to a cow tail holder.

It is the principal aim and object of this invention to provide a device of the above mentioned character designed so that it may be conveniently and quickly connected to the 20 tail of a cow and to the legs of the cow in such a manner as to prevent the cow from moving its tail while being milked.

It is an additional and equally important object of the present invention to provide 25 a device of the above mentioned character wherein the construction is novel in form so that when applied in position the likelihood of accidental displacement is reduced to a minimum.

30 More particularly this invention embraces the provision of a device of the above mentioned character wherein a pair of complementary sections are employed and designed to form tail engaging jaws and leg engaging 35 members being movably and resiliently held together in such a manner that the jaws are normally held in yielding engagement with each other but are capable of being separated by a slight pressure when it is 40 either desired to apply the device or remove the same from position.

It is a further object of this invention to provide a device of the above mentioned character which is simple in construction, 45 thoroughly reliable and efficient in its purpose and inexpensive in manufacture.

Other objects will be in part obvious and in part hereinafter set forth.

The invention accordingly consists in the 50 features of construction, the combination of elements and the arrangement of parts which will be exemplified in the construction hereinafter described and the scope of the application of which will be indicated in 55 the appended claims.

The invention is clearly illustrated in the accompanying drawing, in which—

Figure 1 is a side elevation showing the device applied.

Fig. 2 is a perspective view of the device, 60 and

Fig. 3 is a transverse section thereof.

Similar characters of reference are employed in all of the above described views, to indicate corresponding parts.

65

Referring now, more particularly, to the accompanying drawing, there is provided a pair of complementary sections 1 and 2, each of which consists of a body composed of a straight portion 3 and an inclined portion 4.

4. Arcuate tail engaging jaws 5 are formed on the outer end of the straight portion 3 of the sections 1 and 2 and when the straight portions are held in yielding engagement with each other in a manner that will hereinafter become apparent the jaws 5 are positioned in opposed relation with each other while the outer ends thereof overlap each other, to provide for the accommodating of various sized tails between the jaws. Oppositely extending arcuate leg engaging arms 6 continue from the outer ends of the inclined portion 4 of the sections and in addition to serving as a means for engaging the inner surfaces of the hind legs of a cow act 70

as handles for the spreading of the jaws in a manner that will hereinafter become apparent.

75 80 85

As intimated, improved means have been provided for movably connecting the sections 1 and 2 to each other so that the jaws 5 are normally arranged in close relation with each other. In reducing this feature of the invention to practice, an improved connecting element is employed and is desirably 90

formed of a single piece of resilient wire consisting of an intermediate portion 7 which is positioned between the points of distortion of the straight and inclined portions of the sections as indicated in Fig. 2 95

100 while oppositely extending coils 8 and 9 continue from the intermediate portion and are arranged in close relation with the upper and lower faces of the sections 1 and 2.

Arms 10 project from the coils 8 and 9 and 105 extend in opposite directions with each other crossing the upper and lower faces of the sections 1 and 2 at the meeting edges of the straight portion 3 and terminate in angularly projecting nibs 11 which are fitted 110

in transverse grooves 12 in the opposite or outer faces of the straight portion 3 of the sections 1 and 2, as indicated in Fig. 2. By this arrangement it will be seen that the 5 tension of this resilient connecting element serves to normally hold the straight portion and the jaws 5 in yielding engagement with each other, but upon pressing the inclined portions toward each other it is appreciated that the jaws will be spread so that they 10 may be either applied to or removed from the tail of the cow in a manner as indicated in Fig. 1.

It is believed in view of the foregoing 15 description that a further detailed description of the operation of the invention is entirely unnecessary. Likewise, it is believed that the advantages of this invention will be readily apparent.

20 As many changes could be made in the above construction and many apparently widely different embodiments of this invention could be made without departing from the scope thereof it is intended that all matter 25 contained in the above description or shown in the accompanying drawing shall be interpreted as illustrative and not in a limited sense. It is also to be understood that the language used in the following 30 claims is intended to cover all the generic and specific features of the invention herein described and all statements of the scope of the invention which as a matter of language might be said to fall therebetween.

35 Having thus fully described the invention,

what is claimed as new and desired to be secured by Letters Patent, is:

1. A device of the character described including a pair of complemental relatively movable sections, opposed tail clamping 40 jaws formed at the adjacent terminals of the sections and normally held in close relation with each other, and oppositely extending leg engaging arms continuing from the opposite terminals of the sections and 45 also serving as handles for facilitating the spreading of the jaws when desired.

2. A device of the character described including a pair of complemental sections the body of each of which consists of a 50 straight portion and an inclined portion, an arcuate tail engaging jaw formed at the free terminal of the straight portion, an outwardly extending leg engaging arm continuing from the free terminal of the inclined portion of each section, and a resilient connecting element interposed between and connected to the sections and designed for normally holding the tail engaging jaws in close relation with each other so that the 55 terminals thereof overlap and for holding the leg engaging arms in spreading relation yet permitting of the spreading of the jaws when desired.

In testimony whereof I affix my signature 60 in presence of two witnesses.

PETER H. ALBERT.
